UNITED STATES PATENT OFFICE

152,083

DESIGN FOR A NECKLACE

William W. Hobé, New York, N. Y.

Application September 21, 1948, Serial No. 148,683

Term of patent 3½ years

(Cl. D45—16)

To all whom it may concern:

Be it known that I, William W. Hobé, a citizen of the United States of America, residing in New York city, county of New York, and State of New York, have invented a new, original, and ornamental design for a Necklace, of which the following is a specification, reference being had to the accompanying drawing, forming part thereof, wherein:

Figure 1 is a front elevational view of a necklace, showing my new design.

Figure 2 is a side elevational view of the necklace shown in Figure 1.

The units shown in dotted lines are identical in appearance to the corresponding units shown in full lines.

I claim:

The ornamental design for a necklace, substantially as shown and described.

WILLIAM W. HOBÉ.
